UNITED STATES PATENT OFFICE.

WILLIAM SHAW, OF BALLARD VALE, MASSACHUSETTS.

DESIGN FOR A BADGE.

SPECIFICATION forming part of Design No. 22,745, dated August 29, 1893.

Application filed January 12, 1893. Serial No. 458,187. Term of patent 14 years.

To all whom it may concern:

Be it known that I, WILLIAM SHAW, of Ballard Vale, in the county of Essex and State of Massachusetts, have invented and produced 5 a new and original Design for Badges, of which the following is a specification, reference being had to the accompanying drawing, forming part thereof.

The drawing is a face view of a badge illustrating my new design.

My design consists of an outer circular-rim 4 having a portion removed to form the opening 5 as shown. From the upper portion of the rim extends the projection 6 and from the 15 lower portion of the rim the curved-bar 7 projects being joined to the rim at both ends. Opposite the opening 5, with its ends resting against the rim, is the bar 8 and at each end of this bar 8, connected therewith, is a bar 9,

practically at right angles to the bar 8, extending to and touching the inside of the rim. Near the opening between the bars 9 and generally parallel therewith is the bar 10 which extends on both sides of the bar 8 and is somewhat shorter than the bars 9. Connecting the inner edges of the circular-rim 4, opposite the bar 7 and projection 6, with the bars 9 and 10 is a vertical-bar 11.

What I claim is—

The design for a badge or similar article as 30 herein shown and described.

In witness whereof I have hereunto set my hand.

WILLIAM SHAW.
